UNITED STATES PATENT OFFICE.

RUFUS L. NEAL, OF WASHINGTON, ARKANSAS, ASSIGNOR OF ONE-HALF TO WILLIAM C. GRIFFIN, OF WASHINGTON, ARKANSAS.

FLYING-MACHINE.

1,181,916.

Specification of Letters Patent.

Patented May 2, 1916.

Application filed January 11, 1916. Serial No. 71,537.

To all whom it may concern:

Be it known that I, RUFUS L. NEAL, a citizen of the United States, residing at Washington, in the county of Hempstead 5 and State of Arkansas, have invented a new and useful Flying-Machine, of which the following is a specification.

This invention relates to flying machines of the heavier-than-air type, one of the objects of the invention being to provide a single controlling means by the manipulation of which the horizontal controlling planes or rudders at the front and back ends of the machine can be shifted to direct the 15 machine upwardly or downwardly as desired and which controlling means can also be manipulated to operate aerofoils at the sides of the machine, thus to restore and maintain the lateral balance of the machine.

20 A further object is to improve upon the general construction of the machine so as to render the same durable so as to withstand the various strains to which the machine is subjected while in use.

25 With the foregoing and other objects in view which will appear as the description proceeds, the invention resides in the combination and arrangement of parts and in the details of construction hereinafter described 30 and claimed, it being understood that changes in the precise embodiment of the invention herein disclosed can be made within in the scope of what is claimed, without departing from the spirit of the invention.

35 In the accompanying drawings the preferred form of the invention has been shown.

In said drawings: Figure 1 is a plan view of the machine, the fabric coverings of the 40 wing frames being removed. Fig. 2 is a vertical longitudinal section through the machine. Fig. 3 is a section on line A—B Fig. 2.

45 Referring to the figures by characters of reference 1 and 2 designate the upper and lower longitudinal members of the central or main frame of the machine, these members being bowed and oppositely disposed. Two pairs of the members are employed and 50 the members of the two pairs are connected by cross strips 3 located at desired intervals. Members 1 and 2 are connected together at their ends in any manner desired, as by means of straps 4 secured thereon. 55 End cross strips 5 and 6 also are secured to

the ends of the members 1 and 2, and interposed between said members 1 and 2 at desired intervals are struts or spacing standards 7 whereby collapsing of the frame is prevented. Extending over the members 1 60 directly above the front strut 7 is the front frame member 8 of the sustaining plane, this frame member being held down onto the members 1 by straps 9 extending thereover and suitably secured to the members 1. The 65 rear member of the frame of the sustaining plane has been indicated at 10 and instead of extending over the members 1 is extended under them as shown particularly in Figs. 1 and 2, it being fastened in any manner desired to said members 1. Ribs 11 connect the members 8 and 10 and are attached thereto preferably by upper and lower straps or metal plates 12 bolted or otherwise secured to the parts. Upwardly and 70 outwardly inclined braces 13 are secured to the lower ends of the struts 7 under the members 8 and 10 of the frame of the sustaining plane and are secured at their outer or upper ends to the outer ends of said 75 frame members 8 and 10, these braces being reinforced by suitably disposed struts 14. The entire frame structure thus produced is additionally reinforced by means by crossed guys mounted in a novel manner. These 80 guys, which are preferably formed of steel wire and which have been indicated at the several places on the drawings by the numeral 15, are secured at their ends to eye bolts 16 and these bolts are extended 85 through diagonally disposed corner brackets 17 fastened to the adjacent parts of the frame. The bolts 16 are engaged by nuts 18 and obviously by screwing the nuts onto the bolts the guys can be drawn taut and the 90 frame thus rendered rigid so as to resist strains from all directions.

Secured to certain of the cross strips 3 connecting the members 2 is a boat-like car or body 19 in which is arranged the motor 100 20 which drives the propeller shaft 21. This propeller shaft is journaled in brackets 22 depending from the frame of the sustaining frame and the propeller 23 on said shaft is located in front of the body 19. 105 Any suitable means may be employed for transmitting motion from the motor to the shaft 21. For example, a chain 24 may be employed.

Hingedly connected to the front cross 110

strip 5 is a front controlling plane or horizontal rudder 25 extending back between the members 1 and 2 and toward the car or body 19. Another horizontal rudder or body 5 controlling plane 26 is hingedly connected to the rear cross strip 6 and extends rearwardly therefrom. Projecting upwardly from this cross strip 6 is a guide arm 27 suitably braced as at 28 and another guide 10 arm 29 extends downwardly from the cross strip 6 and is suitably braced as at 30. Additional guide arms 31 extend upwardly from certain of the upper cross strips 3 and mounted in the upper guide arms 31 and 27 15 is a connecting cable 32 one end of which is secured to the rear controlling plane 26 at a point back of the hinge thereof while the other end is connected to the front controlling plane 25 at a point in rear of the hinge 20 thereof. Another cable extends downwardly from the rear portion of the front controlling plane 25, as shown at 33 and extends past a guide 34 and into the car 9 where it is secured to a drum 35 mounted for rotation. Another cable 36 is fastened to the drum 25 and extends rearwardly therefrom through the guide arm 29 and is fastened to the bottom of the rear controlling plane 26. Thus it will be seen that when the drum 35 is rotated in one direction, plane 26 will be elevated at its lower end while plane 25 will be lowered at its lower end and, during the rotation of the drum in the opposite direction, the movement of the two planes will 30 be reversed.

Drum 35 is secured to and supported by a shaft 37 and this shaft is adapted to be actuated by a lever 38 extending radially therefrom and mounted for rotation about 40 its individual longitudinal axis. A handle 39 of any suitable form is located at one end of the lever 38 and by means thereof said lever can be swung back and forth to rotate the drum 35 in either direction. Or if desired, by means of the handle the lever 45 38 can be rotated about its own longitudinal axis. This will result in winding upon said lever a cable 40 extending laterally beyond one side of the machine and unwinding another cable 41 extending laterally beyond the other side of the machine or vice versa. The two cables are secured to the lower faces of side controlling planes or aerofoils 42 which are arranged below the 50 outer end portions of the sustaining planes and are hingedly mounted between depending brackets or hangers 43 secured to the frame of the sustaining plane, the said controlling planes or aerofoils 42 being extended rearwardly from these brackets. Guides 44 are arranged above the rear portions of the side controlling planes and are 55 movably engaged by a connecting cable 45 one end of which is secured to the upper face of one of the planes 42, while the other

end is secured to the upper face of the other plane 42. Thus when shaft 38 is rotated in one direction, the front portion of one plane 42 will be lowered while the corresponding portion of the other plane 42 will be raised. Obviously, from the foregoing, by manipulating the one lever 38 so as to either or both swing it and rotate it, the various controlling planes 25, 26 and 42 can be shifted, the movement of the front and rear planes 75 25 and 26 resulting in the upward or downward movement of the machine or its horizontal flight, while the shifting of the side controlling planes 42 will operate to restore or maintain the lateral balance of the machine. 80

For the purpose of controlling the lateral movement of the machine, a vertical rudder of novel form is provided. This vertical rudder includes parallel vertical planes 85 46 mounted between the rear portions of the pairs of members 1 and 2 and mounted to swing about individual vertical axes at the centers thereof. The said planes are connected at their front and rear ends to 90 form a parallelogram, the connections being of any type desired, as, for example, cross rods 47 pivotally attached to the planes. Cables 48 are attached to the respective planes at the rear ends thereof and 95 extend through a suitable guide 49 and are attached to a lever 50 at points above and below the fulcrum thereof. Thus by shifting the lever 50 in one direction, the two planes 46 will be swung toward the right 100 at their front ends, thus to steer the machine to the left and, when the lever is shifted in the opposite direction, the machine will be guided to the right. 105

Runners 51 may be arranged under the rear portion of the structure and supporting wheels 52 can be located under the front portion thereof or, if desired, any other suitable forms of supports may be employed to maintain the machine in proper position while resting on the ground. The body or carriage 19 is preferably in the form of a boat or pontoon so that the entire structure 110 will float upon a body of water.

What is claimed is:—

1. A frame consisting of members arranged in parallel pairs, the members of each pair being bowed and oppositely disposed and secured together at their front and rear ends, a sustaining plane having 115 its front frame member extending over and secured to the upper members of said pairs and having its rear frame member extending under and secured to the upper members of the said pairs, and a carriage connected to 120 and supported by the lower members of said pairs, and under the frame of the sustaining plane.

2. A frame consisting of members arranged in parallel pairs, the members of 125

- each pair being bowed and oppositely disposed and secured together at their front and rear ends, a sustaining plane having its front frame member extending over and secured to the upper members of said pairs and having its rear frame member extending under and secured to the upper members of the said pairs, front and rear cross strips secured to the ends of the bowed frame members, a horizontal controlling plane hingedly connected to and extended rearwardly from each of said cross strips, and means for simultaneously shifting the planes.
- 5 3. A frame consisting of members arranged in parallel pairs, the members of each pair being bowed and oppositely disposed and secured together at their front and rear ends, a sustaining plane having its front frame member extending over and secured to the upper members of said pairs and having its rear frame member extending under and secured to the upper members of the said pairs, front and rear cross strips secured to the ends of the bowed frame members, a horizontal controlling plane hingedly connected to and extended rearwardly from each of said cross strips, and extending laterally beyond the bowed frame members, a controlling lever, and means operated by the oscillation of the lever for simultaneously shifting said controlling planes to direct the machine upwardly or downwardly as desired.
- 10 4. A frame consisting of members arranged in parallel pairs, the members of each pair being bowed and oppositely disposed and secured together at their front and rear ends, a sustaining plane having its front frame member extending over and secured to the upper members of said pairs and having its rear frame member extending under and secured to the upper members of the said pairs, front and rear cross strips secured to the ends of the bowed frame members, a horizontal controlling plane hingedly connected to and extended rearwardly from each of said cross strips, and extending laterally beyond the bowed frame members, a controlling lever, and means operated by the oscillation of the lever for simultaneously shifting said controlling planes to direct the machine upwardly or downwardly as desired.
- 15 5. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane.
- 20 6. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.
- 25 7. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.
- 30 8. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.
- 35 9. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.
- 40 10. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.
- 45 11. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.
- 50 12. A flying machine including opposed pairs of frame members, the members of each pair being bowed and oppositely disposed and being secured together at their ends, a sustaining plane having the front strip of its frame extended over and secured to the upper bowed member and having its rear strip extending under and secured to the upper bowed member, struts interposed between the bowed members, upwardly diverging braces connecting the lower bowed members to the outer end of the frame of the sustaining plane, struts interposed between said braces and the frame of the sustaining plane, crossed guys, corner brackets connected to portions of the machine, bolts adjustably mounted in the brackets and secured to the guys, and means for adjusting the bolts within the brackets.

In testimony that I claim the foregoing as my own, I have hereto affixed my signature in the presence of two witnesses.

RUFUS L. NEAL.
